UNITED STATES PATENT OFFICE

ALPHONSE E. FELLNER, OF BELLEVILLE, ILLINOIS, ASSIGNOR TO ROESCH ENAMEL RANGE COMPANY, OF BELLEVILLE, ILLINOIS, A CORPORATION OF ILLINOIS

DESIGN FOR A RANGE

Application filed February 27, 1932. Serial No. 43,020. Term of patent 7 years.

To all whom it may concern:

Be it known that I, ALPHONSE E. FELLNER, a citizen of the United States of America, residing at Belleville, county of St. Clair, State of Illinois, have invented a new and original Design for a Range, of which the following is a specification, reference being had to the accompanying drawing, forming part thereof.

The single figure is a perspective view of the range showing my design.

I claim:

The ornamental design for a range, as shown.

ALPHONSE E. FELLNER.
